Specification for Design.

Patented July 4, 1922.

Application filed October 19, 1921. Serial No. 508,879. Term of patent 14 years.

To all whom it may concern:

Be it known that we, WILLIAM F. HOELZER and JOHN T. JOHNSON, both citizens of the United States, and residents, respectively, of New Brunswick, in the county of Middlesex and State of New Jersey, and Plainfield, in the county of Union and State of New Jersey, have invented a new, original, and ornamental Design for Tires, of which the following is a specification, reference being had to the accompanying drawing, forming part thereof.

Figure 1 is a plan view of a portion of a tire of our new design, and

Figure 2 is a cross-section of the same taken on the line 2—2 of Fig. 1.

We claim:

The ornamental design for a tire, as shown.

WILLIAM F. HOELZER.
JOHN T. JOHNSON.
